UNITED STATES PATENT OFFICE.

MARIUS SØRENSEN, OF COPENHAGEN, DENMARK.

METHOD OF LASTING BOOTS AND SHOES.

1,224,229.

Specification of Letters Patent.

Patented May 1, 1917.

Application filed April 6, 1915. Serial No. 19,511.

To all whom it may concern:

Be it known that I, MARIUS SØRENSEN, manufacturer of boots and shoes, a citizen of the Kingdom of Denmark, residing at 5 No. 39 Blaagaardsgade, Copenhagen, Denmark, have invented certain new and useful Improvements in Methods of Lasting Boots and Shoes, of which the following is a specification.

10 This invention refers to a method for wholly or partially lasting boots and shoes by means of a wire loop as lasting-means, the ends of the wire-loop being fastened at the top of the last after the lasting is accomplished. The invention is characterized by the use of a wire-loop as lasting-means, to substitute the work usually done by means of pincers, the ends of the wire-loop crossing each other on the bottom of the 20 last and then passing along the outer sides of the last and finally carried upward to its top.

In the example of this process shown in the drawing, it is supposed that only the 25 front part of the upper is to be lasted in the manner referred to by means of a wire-loop.

Figure 1 is a bottom view of the last with the lasted upper on it.

30 Fig. 2 is a side view of the same.

Fig. 3 shows, on a larger scale, an example of the means used for guiding and fastening the wire-loop, whose ends are fastened at the top of the last.

35 A wire loop 4 for the lasting operation is secured by stitching to the lower edge 5 of the upper which is to be lasted. The ends *a* and *b* project from the stitched edge and are free at the shank of the upper.

40 The upper having said wire loop attached is placed on the last and the free ends *a* and *b* of said loop are passed in opposite directions over the bottom of the last and up the sides thereof between the last and

45 the upper, the end *a* which is connected with the loop at the inside edge of the upper being passed up over the outer face thereof, and the end *b* which is connected with the loop at the outer edge of the last being passed up over the inner face thereof; 50 said ends being preferably crossed diagonally over the bottom of the last. These ends are pulled taut utilizing the sides of the last as bearing surfaces, and then

brought into engagement with holding means.

The preferred holding means is in the form of a clamp mounted in the top of the last. For this purpose the rear portion of the last is provided with a vertical socket. 60 The clamp comprises a vertical rod 9 adapted to fit at its lower end in said socket. This rod is provided at its upper end with a vertical screwthreaded socket 20 in its body and with a shoulder 21 having a conically flaring clamping jaw 8 projecting beyond said socket 20. This jaw is provided with grooves and holes 7 which connect the mouth of the jaw with the base of the shoulder at opposite sides of the rod 9 for the 65 passage of the wires. The other member of the clamping holder consists of a rod 13 provided at its lower end with a reduced screwthreaded tang 12 adapted to fit the screwthreaded socket 20 and with a shoulder 70 30 at the base of said tang. A conical jaw 11 having a central hole is loosely disposed on said tang 12 between the socketed end of the rod 9 and the shoulder 30 of the rod 13. This conical jaw 11 fits within the flaring conical jaw 8 and is moved toward or 75 from said flaring jaw by the turning of the rod 13.

After the free ends *a* and *b* of the wires of the loop 4 are passed up the opposite 80 sides of the last as aforesaid and drawn taut, they are threaded through the holes 7 of the jaw 8 and through said jaw. Then the rod 13 is turned and the conical upper jaw 11 is forced into the flaring hollow 85 90 jaw 8 and said wire ends *a* and *b* are clamped firmly between said jaws.

I claim:

1. The method of lasting shoes and boots, which consists in sewing a wire to the lower 95 edge of the forepart of the upper, placing the upper with the sewn-on wire on the last, crossing the ends of the wire on the bottom of the last, passing the ends of the wire along the outer sides of the last, between the sides of the last and the upper up to the top of the last, then lasting the upper leather by pulling the ends of the wire, and fastening these at the top of the last after the lasting is accomplished. 100

2. In a method of lasting shoes and boots, those steps which consist in sewing a wire to the lower edge of the fore part of the 105

upper, placing the upper with the sewn-on wire on the last, passing the free ends of said wire in opposite directions over the bottom of the last and up between the sides 5 of the last and the upper, drawing said ends taut over the sides of the last, and holding them in their tightly drawn positions.

Copies of this patent may be obtained for five cents each, by addressing the "Commissioner of Patents, Washington, D. C."

In testimony that I claim the foregoing as my invention, I have signed my name in presence of two subscribing witnesses.

MARIUS SÖRENSEN.
